UNITED STATES PATENT OFFICE.

OTIS TIFFANY GREGG AND WILLIAM BURR GREGG, OF HACKENSACK, NEW JERSEY,
ASSIGNORS TO THE GREGG COMPANY, LIMITED, OF HACKENSACK, NEW JERSEY, A
CORPORATION OF NEW YORK.

SIDE-DOOR-CAR CONSTRUCTION.

1,348,170.

Specification of Letters Patent. Patented Aug. 3, 1920.

Application filed August 2, 1916. Serial No. 112,740.

To all whom it may concern:

Be it known that we, OTIS TIFFANY GREGG and WILLIAM BURR GREGG, citizens of the United States, residing at Hackensack, in 5 the county of Bergen and State of New Jersey, have invented certain new and useful Improvements in Side-Door-Car Construction; and we do declare the following to be a full, clear, and exact description of 10 the invention, such as will enable others skilled in the art to which it appertains to make and use the same, reference being had to the accompanying drawings, and to the letters and figures of reference marked 15 thereon, which form a part of this specification.

Our invention relates to side door cars more particularly of the type of cars for transporting cane but applicable for other 20 uses. The object of the invention is to provide a construction characterized by simplicity and strength in its various parts and by which the cost of production is materially decreased. To the accomplishment of 25 the foregoing and such other objects as may hereinafter appear the invention consists in the features hereinafter particularly described and then sought to be clearly defined by the claims, references being had to the 30 accompanying drawings forming a part hereof, and in which—

Figure 1 is a side elevation of a portion of a car formed according to the present invention, and showing the side unfastened 35 and swung partially open;

Fig. 2 is a perspective of a portion of the car on a larger scale, and showing the side fastened in its closed position;

Fig. 3 is a section on the line 3—3 of Fig. 40 1 showing the manner of hinging the upper ends of the bars constituting the side door;

Fig. 4 is a section on the line 4—4 of Fig. 1 showing the manner of securing the lower 45 ends of the bars constituting the side door to the bottom rail of the door.

In Fig. 1 is illustrated a type of car which has a central partition dividing the car into two compartments, each compartment having side dump doors, but the invention is the same whether applied to that 50 or other type of construction.

In the drawings the numeral 1 designates the floor frame of the car of any approved type, and 2 designates the sides of the car

and 3 the ends and 4 the central partition 55 if such be used, the several parts mentioned being preferably formed of metal. The top belt-rails or horizontally arranged bars 5 of the car body frame are preferably of commercial Z shaped metal bolted or riveted 60 at suitable points to the upper ends of upright posts or members 6 which preferably are of commercial L shaped metal, although they may be other formation, the lower ends of the uprights being suitably bolted or riveted 65 to the metal side sills 1 of the car bottom frame.

The side doors are each formed of a desired number of upright bars 7, preferably formed of commercial L shaped metal, the 70 upper ends of which are pivotally connected or swung by bolts 8 passed through metal brackets 9 attached by rivets 10 to the under face of the horizontal member or web of the Z shaped top belt-rail 5 as shown in Figs. 1 75 and 3, while the lower ends of the bars are secured by bolts 11 or otherwise to L shaped brackets 12 secured preferably by rivets 13 to the bottom rail 14 of the door which is preferably formed of channel iron as shown. 80

The top belt-rail 5 is disposed or positioned so that while the two flanges thereof will be vertical, for the purposes of the present invention, the outer flange is made to extend downwardly and the inner flange upwardly. This is done so that with the stakes, forming part of the door, swung from the belt-rail as hereinafter specified the maximum strength of the Z belt-rail will be availed of to resist the strains which occur, 90 and the downward and outward pressures which are developed will be so distributed that the downward pressure will be approximately along the vertical center line of the Z belt-bar and the outward pressure approximately along the horizontal line of the same bar and thus avoiding the strain of twisting or torsion exerted on the belt-bar as the result of the downward and outward pressures developed under other constructions. 95

Under the improved construction the upper portions of the stakes constituting a portion of the door bear against the inner edges of the hinging brackets at a point quite close to the web of the Z belt-bar when the door 100 is in its closed position as illustrated in full lines in Fig. 3 of the drawing, and the point of hinging the stakes to the brackets is suf- 105

ficiently below the lowest part of the downwardly extending outer flange of the belt-bar to permit the doors to open to the necessary extent before the stakes strike the lower edge of the outer downwardly extending flange of the belt-bar. These features of construction cause the downward pressure to be substantially through the center-line of the belt-bar as indicated by the line *a—a* 10 of Fig. 3, and the outward pressure to be substantially along the horizontal line of the bar as indicated by the line *b—b*, thus avoiding the twisting or torsional action on the bar as previously mentioned; and the 15 positioning of the **Z** belt-bar with its outer flange extending downwardly and its inner flange upwardly making possible the utilizing of the maximum strength of the bar to resist the strains imposed where the construction comprises generally a **Z** belt-rail 20 from which is swung a hinged side-door and the belt-rail disposed with its flanges extending oppositely to what is provided for in this improved construction. With the parts arranged as herein described the upper ends of the stake bars are cut away or formed on an incline as indicated at *c* so that the stakes may swing without interference with the rivets 10 by which the hinging brackets 25 9 are supported from the belt-bar. In the manner described a specially strong and comparatively inexpensive construction of door is provided and one which is easily manipulated in opening and closing.

30 95 The door is locked or fastened in its closed position by a link lever 15 preferably formed of looped parallel arms passed through an eye 16 of a bracket 17 bolted to the sill of the car and having its upper ends 40 welded together so as to provide a lever simple and strong and capable of securely holding the door closed against pressure exerted from within the car or otherwise.

Any suitable lock or holder for effecting 45 locking engagement between the lock lever and door may be employed but the preferred construction on account of strength and security consists of an open faced metal pocket 18 provided with a swinging latch 19 adapted to be tilted on its pintle 20 so that its free end may engage or interlock with the nose or catch 21 of the holder and securely hold the lever in the pocket when the door is in its closed position. This metal pocket or 50 55 holder is bolted or otherwise secured to a base-plate 22 preferably formed of channel iron and which is secured by bolts 23 or otherwise to two of the upright bars constituting a part of the door as shown. When 60 65 the door is to be opened the latch 19 is lifted from out of engagement with the nose 21 of the pocket and swung on its pivot pin or pintle 20 so as to open the face of the pocket and permit the lever to be lowered or dropped and then the door is free to swing

outward as indicated in Fig. 1 and by dotted line in Fig. 3 so that the cane or other contents of the car may be discharged or dumped.

It will be observed that the locking lever 70 15 is connected to the side sill of the car by an eye-bolt so that the lever is free to swing laterally as well as vertically and thus danger of accidental bending of the lever is avoided; also that by attaching the locking 75 lever at one end by a substantially universal joint to the car side sill so that it may pass over the lower rail of the door and have its upper end fastened to the door above the bottom rail and about substantially centrally 80 or midway between the two ends of the door, the outward pressure of the door on the lower rail of the door is considerably reduced as the pressure is largely taken by the lever above and below the rail. This also 85 contributes to greater ease in releasing the locking lever when the car is loaded. It also dispenses with the necessity of employing a number of lock fastenings for the door and thus the secure locking and release is expedited and otherwise facilitated and it is 90 made possible to construct the several parts heavier than otherwise so that simplicity and increased strength and durability are obtained with a saving of cost in construction. 95

We have illustrated and described with particularity the preferred details of the several parts but changes may be made without departing from the essential features of the invention. 100

We claim—

1. In cars, a side-door therefor comprising vertically disposed stake-bars connected together by a bottom rail, and a **Z**-shaped 105 supporting belt-rail disposed with its outer flange extending downwardly and its inner flange upwardly, the upper ends of the stake-bars having a hinged connection with the belt-rail.

2. In cars, a side-door therefor comprising vertically disposed stake-bars connected together by a bottom rail, a **Z**-shaped supporting belt-rail disposed with its outer flange extending downwardly and its inner 115 flange upwardly, bracket-hangers for the door stake-bars supported from the belt-rail, and means pivotally connecting the upper ends of the stake-bars with the bracket-hangers at a point relatively to the 120 lower end of the depending outer flange of the belt-rail to permit the stake-bars to swing outwardly beneath said flange. 110

3. In cars, a side-door therefor comprising vertically disposed stake-bars connected 125 together by a bottom rail, a **Z**-shaped supporting belt-rail disposed with its outer flange extending downwardly and its inner flange upwardly, bracket-hangers for the door stake-bars supported from the belt-rail, 130

- and means pivotally connecting the upper ends of the stake-bars with the bracket-hangers to permit the stake-bars to swing outward beneath the depending flange of the belt-rail, the upper ends of the stake-bars being formed with portions to bear against the inner edges of the brackets when the door is closed.
4. In cars, a side-door therefor comprising vertically disposed stake-bars connected together by a bottom-rail, a Z-shaped supporting belt-rail disposed with its outer flange depending downwardly and its inner flange upwardly, bracket-hangers for the door stake-bars supported from the belt-rail, and means pivotally connecting the upper ends of the stake-bars with the bracket-hangers to swing outward beneath the depending flange of the belt-rail, the stake-bars having upper ends receding or inclined in the direction of the depending flange of the belt-rail for free swing of the stake-bars.
5. In cars, a side door therefor hinged at its upper end to swing outwardly, and locking means for holding the door closed consisting of a single releasable locking member located approximately midway between opposite ends of the door and having one end attached to a part of the car below the door and the other end to the door at a substantial distance above the bottom of the door to adapt the locking member to be thrown outwardly by outward pressure of the door from within the car when the upper end of said member is released.
6. In cars, a side door therefor comprising vertical stake-bars hinged at the top to swing outwardly and having a lower connecting rail, and means for locking the door consisting of a swinging member located approximately midway between opposite ends of the door with one end attached to a part of the car below the door and extending across the bottom rail of the door and parallel with the stake-bars, to adapt the swinging member to be thrown outwardly by outward pressure of the door from within the car when the upper end of said member is released.
7. In cars, a side-door therefor comprising vertical stake-bars hinged at the top to swing outwardly and having a lower connecting rail, and means for locking the door consisting of a swinging member having an eye-hinge universal connection with a part of the car below the door and adapted to extend across the bottom rail of the door and parallel with the stake-bars, to adapt the swinging member to be thrown outwardly by outward pressure of the door from within the car when the upper end of the swinging member is released, and means for releasably attaching the free end of the member to the door above its bottom rail.
8. In cars, a side-door therefor comprising upright bars, and means for holding the door closed, said means comprising a latch pocket-member attached to adjacent upright bars and located between said bars, and a swinging member connected with the car-floor frame and located to enter the latch pocket-member.
9. In cars, a side-door therefor comprising upright bars, and means for holding the door closed, said means comprising a latch pocket-member attached to adjacent upright bars and located between said bars, and a swinging member looped through an eye secured to the car-floor frame and consisting of parallel members positioned relatively close to each other and whose free end is adapted to enter the latch pocket-member.
